UNITED STATES PATENT OFFICE.

LUD. HOLLAND-LETZ, OF OAK PARK, ILLINOIS, ASSIGNOR, BY MESNE ASSIGNMENTS, TO INTERNATIONAL HARVESTER COMPANY, A CORPORATION OF NEW JERSEY.

BUCKLE SLAT FOR CONVEYERS.

Application filed August 5, 1918. Serial No. 248,466.

To all whom it may concern:

Be it known that I, LUD. HOLLAND-LETZ, a citizen of the United States, residing at Oak Park, in the county of Cook and State of Illinois, have invented certain new and useful Improvements in Buckle Slats for Conveyers, of which the following is a full, clear, and exact specification.

My invention relates to conveyers and especially to a buckle slat for conveyers.

Conveyers or aprons used to carry grain and like material are usually provided with cross slats and also with longitudinal straps, the straps of one portion of the conveyer having buckles attached thereto which co-operate with the corresponding straps carried by the other end of the conveyer. The use of these slats sometimes gives rise to difficulty in the mounting of the buckles on the straps and this is more particularly true when the slats and straps are employed on circular or quadrantal conveyers, since when used with this type of conveyer the slats converge at one side of the conveyer and diverge at the outer side. Because of the converging of the slats sufficient space for the mounting of the buckles between the slats is not provided.

Another difficulty which has been encountered is that of maintaining the buckles on the different straps in alinement with each other across the conveyer.

Having these difficulties in mind the object of my present invention is to provide a construction whereby the space on the apron is conserved and the buckles will be properly alined.

The object of the invention above stated is attained in the present embodiment by forming the buckles on one of the cross slats of the conveyer.

One embodiment of the invention is illustrated in the accompanying drawings, and in these drawings,—

Figure 1 shows in plan view a portion of a quadrantal conveyer equipped with my improved buckle slat;

Fig. 2 is an enlarged view of a portion of the conveyer shown in Fig. 1;

Fig. 3 is a sectional view of the construction shown in Fig. 2; and

Fig. 4 is a cross sectional view on an enlarged scale, the view being taken through the buckle tongue and the cooperating slat portions.

In Fig. 1 I have illustrated a portion of a quadrantal conveyer 10 having a series of slats 11 carried thereby, these slats radiating from the center of curvature of the conveyer,

The conveyer is also provided with a series of straps 12 conforming in curvature to the curvature of the conveyer. The slats 11 are provided with upstanding lugs 13 which engage the grain being carried around by the conveyer. In the place of the usual buckles carried by the straps 12, I have substituted a buckle slat 14 which is rigidly secured to the conveyer and straps 12 in a manner hereinafter described, and takes the place of one of the slats 11 described above.

The details of the buckle slat are shown in Figs. 2 to 4, and as illustrated therein the slat is preferably formed of sheet metal and has a horizontal body portion 15, a vertical web portion 16 and a rearwardly extending substantially horizontal flange portion 17. The body portion 15 of the slat is provided at spaced intervals throughout its length with a series of slots 18, the material punched out of the body portion to form these slots being bent upwardly and forwardly to form the strap engaging or supporting portion 19 which cooperates with the tongue 20 of the buckle in holding the strap in its adjusted position. The tongue 20 of each of the buckles is provided with a transverse slot 21 which is engaged by a forwardly and downwardly curved portion 22, the latter portion being formed by punching out a portion of the vertical web 16, this operation also forming a slot 23 in said web portion which registers with the slot 18 in the horizontal body portion of the slat.

As clearly shown in Fig. 4, the tongue retaining portion or member 22 is bent downwardly into contact with the upper surface of the horizontal body portion 15 of the slat. The ends of the buckle slat are provided with flanges 24, the flange at the inner end of the slat forming a bearing for the slat 100 and contacting with the rim of a wheel 25 which guides the slats and conveyer in the travel around the conveyer rollers, one of which is shown at 26.

The body portion of the conveyer 10 and the straps 12 are secured to the body portion 15 of the buckle slat by means of a member 27 having a flanged serrated peripheral portion 28, the serrations of the flange extending in the straps 12 as shown 110

2

in Fig. 4. Rivets 29 extend through the members 27 and through the straps, conveyer and body portion 15 of the buckle slat. The path of the strap through the buckle is shown in the section in Fig. 4 and as illustrated therein the strap is passed around the engaging and supporting portion 19 over the pivoted tongue 20 and rearwardly through the slot 23. The pivoted tongue is provided on its front edge with a series of teeth 30 which project into the strap and firmly secure it in adjusted position.

From the above description it will be seen that by providing a slat having the buckles formed thereon, in the place of one of the ordinary slats of a conveyer, the space on the conveyer is conserved and the buckles are always in correct alinement with each other.

While I have shown my invention in connection with a quadrantal conveyer, it should be of course understood that the buckle slat may be used on any conveyer where its use would be desirable.

In disclosing my invention I have illustrated and described one embodiment thereof, but it should be understood that the invention is capable of modification, and that modifications may be employed without departing from the spirit and scope of the invention as expressed by the following claims.

1. A slat for conveyers provided with a strap engaging portion, said slat having a buckle member pivotally carried to one side of and coacting with said portion.

2. A slat for conveyers having a series of buckle tongues pivoted thereto, means formed on said slat adjacent the front ends of said tongues for supporting and engaging a plurality of straps, and means carried by said slat for receiving and guiding the free ends of said straps.

3. A slat for conveyers having a horizon-

tal body portions and a continuous vertical web portion, and a buckle tongue pivotally supported adjacent said portion.

4. A slat for conveyers having a horizontal body portion and a substantially vertical web portion, a buckle tongue pivotally carried intermediate said portions, and means carried by one of said portions and engaging the other for pivotally securing said tongue to said slat.

5. A slat for conveyers having a horizontal body portion and a vertical web portion extending throughout the length of the slat, a tongue pivoted to said slat, said slat having a slot in said horizontal portion and in said vertical position and positioned in alinement with the free end of said tongue when said tongue is in its operative position.

6. A slat for conveyers having a horizontal body portion and a vertical web portion and a tongue pivoted to said slat, said horizontal portion having a slot disposed adjacent the free end of said tongue when said tongue is in operative position, and said vertical web having a slot disposed in alinement with the slot in said horizontal portion.

7. A slat for conveyers having a plurality of angularly disposed portions, a tongue pivoted to said slat, said angularly disposed portions having slots disposed in alinement with the free end of said tongue.

8. A slat for conveyers having a substantially horizontal body portion and a substantially vertical web portion said horizontal portion having an upturned strap engaging portion, and a tongue pivoted to said slat at the junction of said horizontal portion with said vertical portion for cooperating with said upturned portion.

85
In testimony whereof I affix my signature.

LUD. HOLLAND-LETZ.
